PORTABLE OUTDOOR BARBECUE

Robert A. Berliner, North Hollywood, and Arpad P. Augusztiny, Sierra Madre, Calif.; said Augusztiny assignor to said Berliner

Application April 20, 1956, Serial No. 41,145

Term of patent 7 years

(Cl. D81—10)

Fig. 1

We claim:

The ornamental design for a portable outdoor barbecue, substantially as shown.
